UNITED STATES PATENT OFFICE.

ANTHONY W. GEIGAND AND JOSEPH J. GEIGAND, OF BUFFALO, NEW YORK.

DESIGN FOR A NUTCRACKER.

55,460.

Specification for Design.

Patented June 15, 1920.

Application filed April 15, 1920. Serial No. 374,234. Term of patent 14 years.

To all whom it may concern:

Be it known that we, ANTHONY W. GEIGAND and JOSEPH J. GEIGAND, citizens of the United States, residing at Buffalo, in the county of Erie and State of New York, have jointly invented a new, original, and ornamental Design for Nutcrackers, of which the following is a specification, reference being had to the accompanying drawing, forming part thereof, and in which—

Figure 1 is a perspective view of the nut cracker taken from the front side thereof, and Fig. 2 is a perspective view of the same taken from the rear side thereof.

We claim:

The ornamental design for a nutcracker, as shown.

ANTHONY W. GEIGAND.
JOSEPH J. GEIGAND.
